METHOD AND APPARATUS FOR TREATING
FIBROUS CONTAINERSHarold A. Bergstrom, Van Wert, Ohio, assignor
to The Container Company, Van Wert, Ohio,
a corporation of Ohio

Application October 22, 1940, Serial No. 362,301

12 Claims. (Cl. 34—21)

My invention relates to a method and apparatus for treating fibrous containers. It has to do, more particularly, with a method and apparatus for drying, baking, or freeing from solvent odors, coating materials applied to containers made of fiber board or other fibrous materials.

In the application of various coating materials to either the inside or outside of fibrous containers, it is sometimes necessary to bake the coating at such a high temperature that if the entire container was subjected to such a temperature in a conventional oven, the material of the container would become charred, warped, or otherwise damaged. Likewise, certain coating materials applied to such containers must be given a high temperature baking treatment in order to free them of solvent odors.

One of the objects of my invention is to provide a method and apparatus for treating fibrous containers of such a nature that either the inside or outside coating applied thereto may be subjected to a high temperature without excessive heating of the material of which the container is made.

Another object of my invention is to provide a method and apparatus of the type indicated which is of such a nature that the inside or outside coating on the container may be subjected to a temperature above that which the material of the container could stand without becoming charred, warped, or otherwise damaged.

Another object of my invention is to provide a simple method and apparatus for accomplishing the results indicated above in a very efficient and economical manner.

According to my invention, the coating applied either to the inside or outside of the fibrous container is subjected to a "flash" heating operation to bake, dry, or free it from solvent odors. This is accomplished, according to the preferred embodiment of my invention, by means of an apparatus which subjects either the inside or the outside of the container to currents of very hot air or other gaseous medium. However, the inside or the outside of the container is subjected to this hot air for a short period only which is sufficient to dry or bake the coating but which is insufficient to cause penetration of the heat into the material of the container and cause injury thereto.

The preferred embodiment of my invention is illustrated in the accompanying drawings where in similar characters of reference designate corresponding parts and wherein:

Figure 1 is a longitudinal vertical sectional view

taken through apparatus constructed according to my invention for heating the interior coating applied to fibrous containers.

Figure 2 is a plan view of the structure shown in Figure 1.

Figure 3 is a transverse vertical sectional view taken substantially along line 3—3 of Figure 1.

Figure 4 is a view similar to Figure 1 but showing an apparatus for heating the exterior coating applied to fibrous containers.

Figure 5 is a transverse vertical sectional view taken substantially along line 5—5 of Figure 4.

Figure 6 is a horizontal sectional view taken substantially along line 6—6 of Figure 5.

With reference to the drawings, and particularly to Figures 1 to 3 inclusive, I have illustrated an apparatus for baking interior coatings to "flash" heating "according to my invention." This apparatus comprises an oven 1 which has walls of suitable refractory or heat insulating material. This oven can be either directly or indirectly fired or heated with gas, steam, electric heating units, or any other source of heat energy. For illustrative purposes, I have shown a gas burner 2 in the lower part of the oven.

A duct 3 is disposed in the lower part of the oven 1 and passes outwardly through an end wall thereof. This duct 3 is preferably connected to the inlet side of a fan 4 disposed outside the oven. The outlet or pressure side of the fan 4 has a duct 5 connected thereto which leads into a lower portion of the oven at a point beneath the duct 3 and communicates with the interior of the oven. The duct 3 is provided with vertically disposed branches 6 and 7 which are spaced from each other and which extend upwardly through large openings 8 and 9 formed in the upper wall of the oven. Surrounding the opening 8 is a ring 10 which has a seat 11 for receiving the end of the container and centering it over the opening 8. Similarly surrounding the opening 9 is a ring 12 which has a seat 13 for receiving the end of the container. The rings 10 and 12 are removably bolted in place and may be replaced with rings of different sizes depending upon the diameter of the container being heated.

Surrounding the branch 6 of the duct 3 in the oven is a collar 14 which is adapted to be moved vertically on the branch 6. In its uppermost position, this collar 14 is adapted to contact with the inner surface of the upper wall of the oven and to close the annular space in the opening 8 around the branch 6. Within the branch 6 is a

damper 15 which is keyed to a pivot pin 16. The damper 15 and the collar 14 are adapted to be moved simultaneously. When member 14 is in its lowermost position, the damper 15 is open. When member 14 is moved to its upper position to close the opening 8, the damper 15 is closed. For causing the members 14 and 15 to operate together they are connected together by suitable linkage. Thus, a lever 17 has one end keyed to the end of pivot 16 of the damper. The other end of this lever is pivoted at 18 to the lower end of a link 19 which has its upper end pivoted to member 14, as at 20. Thus, when member 14 is moved upwardly, the lever 17 will be swung upwardly and will close damper 15. Associated with the branch duct 7 is an identical arrangement of members 14 and 15 and their connecting parts.

It is desirable in using this apparatus to alternately place over the upper end of branch ducts 6 and 7 a container C to be heated. In Figure 1 the container is shown in inverted position over the branch 6 while the container has been removed from the branch 7. It is desirable to have the damper 15 open and the member 14 in its lowermost position when a container is positioned over the branch duct with which these members are associated. Furthermore, it is desirable to have the damper 15 closed and the member 14 in its uppermost position when a container has been removed from the branch duct with which these members are associated. Therefore, I provide a pair of levers 21 which are keyed midway between their ends to a shaft 22. This shaft 22 is rotatably mounted in supports 23 disposed on the top wall of the oven. The shaft 22 may be rotated by means of a handle 24 keyed to one end thereof. Each end of each lever 21 is connected pivotally as at 25 to the upper end of a rod 26. This rod 26 has its lower end fastened to one of the members 14, as at 27. Thus, it will be apparent that when the handle 24 is swung in one direction, the member 14 of one unit will be raised and the damper 15 of such unit will be closed, while the member 14 of the other unit will be lowered and the damper 15 of such unit will be opened.

In the operation of this oven, a container C is positioned on one of the branch ducts, for example duct 6 as indicated in Figure 1. The fan 4 will be in operation and will force air through the oven and upwardly through the opening 8. During its passage through the oven, the air will be heated to that high temperature necessary to properly treat the coating on the inside of the container. The hot air or gases will pass upwardly along the side walls of the container and then across the end of the container before being drawn downwardly through the branch 6 into the exhaust duct 3. The branch duct 6 should extend up into the container almost to the closed end thereof so that the entire inner surface of the container will be subjected to the hot air and there will be minimum opportunity for dead pockets or eddy currents to develop. The fan 4 will cause the hot gases to quickly circulate through the container. The container need only be positioned on the duct 6 for a short period to properly treat the coating. During the treatment of the container which is positioned over a branch duct 6, the other container will be removed from the branch duct 7 and another will be repositioned thereon. At this time, the member 14 will be in closing relationship to the opening 9 and the damper 15 disposed in branch 7 will be closed. This will prevent escape and waste of the hot air from the oven and will also

prevent drawing in of atmospheric air by the fan 4. The hot air of the oven is continuously circulated by the fan 4 substantially without being diluted by atmospheric air. Thus, the apparatus may operate very economically.

Obviously, similar results can be secured by rearrangement of the apparatus. For example, the direction and flow of the air may be reversed. The principal object is to subject one side only of the container to the high temperature air while the other side is kept relatively cool, being exposed to the atmosphere. Since high temperature air or gas is used, the length of treatment can be shortened so that the heat will not have time enough to penetrate into the material of the container to an extent whereby it will char, warp, or otherwise damage the material. At the same time, the coating film is directly in contact with the high temperature air or gas and reaches the temperature desired almost instantaneously. In practice, short bakes of 600° F. have been applied without the material of the container becoming more than warm to the touch and with no apparent damage to the container proper which normally will not stand a temperature over 400° F. For example, synthetic resin coatings may be subjected to a temperature of 600° for a period of one to two minutes to dry it and remove the solvents without charring or damaging the fiber board of the container.

In Figures 4, 5 and 6, I have illustrated apparatus for accomplishing similar results for treating the coating on the exterior of a fibrous container. In this instance, the oven 1a is constructed substantially as before. A duct 3a is provided and it has branches 6a and 1a vertically disposed. However, these branches have formed on their upper ends container-receiving chambers 6b and 1b which have their upper edges spaced from the top wall of the oven to provide the spaces 6c and 1c. The openings 8a and 9a in the top wall of the oven receive removable rings 10a and 12a which are adapted to be just slightly larger than the container being treated so as to allow downward passage of the container therethrough. The chamber 6b is provided with radial supports 11a on which the lower end of the container will rest while the chamber 1b is provided with similar supports 13a. A ring or collar 14a is mounted on the chamber 6b for vertical movement. When in its uppermost position, this ring will close the space 6c. This ring 14a is connected to a damper 15a disposed in duct 6a by means of linkage 17a substantially like that described in connection with the apparatus shown in Figures 1 to 3. When the ring 14a is moved to its uppermost position, the damper 15a will be closed and vice versa. The damper 15a and ring 14a of the other unit are identical with those just described.

When the ring 14a of one of the units is in its lowermost position and the damper 15a is open, it is desirable that the ring 14a of the other unit be in its uppermost position and the damper 15a of such unit be closed. For this purpose I provide levers 21a which have their opposite ends connected to the two members 14a by rods 26a. By means of handle 24a, one of the members 14a will be raised while the other is lowered.

In using this apparatus, a container is dropped through one of the rings 10a, for example, the one to the right of Figure 4, and it will rest in chamber 6b on the supports 11a. The upper end of the container C will still extend within the ring 10a to prevent escape of hot air at this point.

The hot air will be forced upwardly through the oven and then will be drawn downwardly through space 6c, through chamber 6b in contact with the side walls of the container and then underneath the container and on downwardly through the duct 6a. When the container has been heated for a sufficient time, it may be removed by a suitable expanding tool which may be inserted therein. At the time this one container is being treated, the ring of the other unit 14a will close the space 1c and the damper 15a of the other unit will be closed. Thus, the hot air will be prevented from escaping from the oven and the atmospheric air will not be drawn in through the branch duct 1a. During treatment of this container, a container previously in the chamber 7b may be removed and a different one to be treated positioned therein.

Thus, with this arrangement, the exterior coating on a fibrous container may be subjected to a "flash heating" operation. The interior surface of the container will be in contact with the atmosphere. Thus, overheating will be precluded.

It will be apparent from the above description that I have provided a method and apparatus having many advantages. A number of important advantages have been discussed and others will be readily apparent.

Having thus described my invention, what I claim is:

1. The method of treating a hollow container made of fiber board having a coating substance applied to one surface of the wall thereof which comprises subjecting the coated surface for a period of from one to two minutes to a temperatures of from 400° to 600° F. while simultaneously subjecting the other surface of the wall of the container to a relatively cool medium to prevent injury to the wall of the container.

2. The method of treating a hollow container made of fiber board having a coating substance applied to one surface of the wall thereof which comprises circulating in contact with said surface for a period of approximately one minute hot gases maintained at a temperature of substantially 600° F. while simultaneously subjecting the other surface of the wall of the container to a relatively cool medium to prevent injury to the wall of the container.

3. The method of treating a hollow container made of fiber board having a coating substance applied to the inner surface of the wall thereof which comprises circulating in contact with said inner surface for a period of from one to two minutes hot gases maintained at a temperature of from 400° to 600° F. while simultaneously subjecting the outer surface of the wall of the container to a relatively cool medium to prevent injury to the wall of the container.

4. The method of treating a hollow container made of fiber board having a coating substance applied to the outer surface of the wall thereof which comprises circulating in contact with said outer surface for a period of from one to two minutes hot gases maintained at a temperature of from 400° to 600° F. while simultaneously subjecting the inner surface of the wall of the container to a relatively cool medium to prevent injury to the wall of the container.

5. A method according to claim 2 wherein the said other surface is exposed to the atmosphere.

6. Apparatus for treating a fibrous container having a coating substance applied to the exterior wall thereof, comprising a heating oven, means for circulating hot gases in said oven, a support

for the container adapted to position the container with its inner surface disposed in contact with the atmosphere, said circulating means being of such a nature that the hot gases will be circulated in contact with the exterior surface of the container.

7. Apparatus for treating fibrous containers having a coating substance applied to the exterior thereof comprising a heating oven, multiple openings formed in the upper wall of said oven, multiple container-receiving chambers in communication with said openings, means for supporting containers within said chambers, means for circulating hot gases from said oven through said chambers in contact with the exterior surfaces of said containers, and control means for interrupting the circulation through any one of said chambers while simultaneously producing circulation through other of said chambers.

8. Apparatus for treating hollow fibrous containers having a coating substance applied to the interior surface thereof comprising a heating oven, a plurality of container treating units associated with said oven, each of said units including an opening formed in a wall of said oven, a conduit projecting through said opening and over which a container is adapted to be slipped with its bottom spaced from the outer end thereof and with its open end surrounding said opening, said conduit being disposed in spaced relationship to the edge of the opening to form an outlet through which hot gases may pass from said oven into the container, an exhaust passage connected to the conduit, a blower connected to said exhaust passage, an inlet passage connected to said blower and in communication with said oven to exhaust gases from said exhaust passage and force them into the oven, said conduit having a valve associated therewith for controlling flow of exhaust

gases therethrough and said outlet having a valve associated therewith for controlling flow of the gases therethrough, means for simultaneously closing and opening said valves, and control means for synchronizing operation of said last-named means of the various units so that when the valves of one of said units are closed the valves of another unit are open.

9. Apparatus for treating hollow fibrous containers having a coating substance applied to the interior surface thereof comprising a heating oven having an opening formed in a wall thereof, a conduit projecting through said opening and over which a container is adapted to be slipped with its bottom spaced from the outer end thereof and with its open end surrounding said opening, said conduit being disposed in spaced relationship to the edge of the opening to form an outlet through which hot gases may pass from said oven into the container, an exhaust passage connected to said conduit, a blower connected to said exhaust passage, an inlet passage connected to said blower and in communication with said oven to exhaust gases from said exhaust passage and force them into the oven, said conduit having a valve associated therewith for controlling flow of exhaust gases therethrough and said outlet having a valve associated therewith for controlling flow of the gases therethrough, and means for simultaneously closing and opening said valves.

10. Apparatus for treating hollow fibrous containers having a coating substance applied to the exterior surface thereof comprising a heating oven, a plurality of container-treating units associated with said oven, each of said units including an opening formed in a wall of said oven through

which a container may be passed, a container-receiving chamber disposed within said oven, said container-receiving chamber being in line with said opening and having supporting means associated therewith for supporting the container in such a manner that its bottom is spaced from the inner end of the chamber, its open end extends within said opening and its side wall is spaced from the side wall of the chamber, the outer end of said chamber being provided with an inlet for permitting heated gases from said oven to flow into said chamber, a conduit connected to the inner end of said chamber, an exhaust passage connected to the conduit, a blower connected to said exhaust passage, an inlet passage connected to said blower and in communication with said oven to exhaust gases from said exhaust passage and force them into the oven, said conduit having a valve associated therewith for controlling flow of exhaust gases therethrough and said chamber inlet having a valve associated therewith for controlling the flow of gases therethrough, means for simultaneously closing and opening said valves, and control means for synchronizing operation of said last-named means of the various units so that when the valves in one of said units are closed the valves in another unit are open.

11. Apparatus for treating hollow fibrous containers having a coating substance applied to the exterior surface thereof comprising a heating oven having an opening formed in a wall thereof through which a container may be passed, a container-receiving chamber disposed within said oven, said container-receiving chamber being in line with said opening and having an inlet from the oven adjacent its outer end, a supporting means associated with said chamber for supporting the container in such a manner that its bot-

tom is spaced from the inner end of the chamber, its open end extends within said opening and its side wall is spaced from the side wall of the chamber, a conduit connected to the inner end of said chamber, an exhaust passage connected to said conduit, a blower connected to said exhaust passage, an inlet passage connected to said blower and in communication with said oven to exhaust gases from said exhaust passage and force them into the oven, said conduit having a valve associated therewith for controlling flow of exhaust gases therethrough and said chamber inlet having a valve associated therewith for controlling the flow of gases therethrough, and means for simultaneously closing and opening said valves.

12. Apparatus for treating hollow fibrous containers having a coating substance applied to one surface of the wall thereof comprising a heating oven having an opening formed in a wall thereof, means for supporting a container in association with said opening with its open end in communication with said opening, a conduit associated with said container for cooperating therewith to produce a passageway through which heated gases from the oven will pass for contacting with said coating substance, said passageway having an inlet connected to the oven and having an outlet, an exhaust conduit connected to said outlet, a blower connected to said exhaust conduit, an inlet passage into the oven connected to said blower to exhaust gases from said exhaust conduit and force them into the oven, a valve associated with said passageway for controlling flow of exhaust gases therethrough, a valve for controlling the inlet to said passageway, and means for opening and closing both of said valves simultaneously.

HAROLD A. BERGSTROM.
